(57) CLAIM

The ornamental design for a game board having a set of game pieces, as shown and described.

DESCRIPTION

1. Game board having a set of game pieces

1.1 is a front, right, top perspective view of a game board having a set of game pieces comprising a game board and a set of game pieces, showing our new design in an exploded state;

1.2 is a front, right, top perspective view of the game board shown separately for clarity of disclosure;

1.3 is a back, left, top perspective view thereof;

1.4 is a top plan view thereof;

1.5 is a bottom plan view thereof;

1.6 is a front elevational view of the game pieces shown separately for clarity of disclosure;

1.7 is a back elevational view thereof;

1.8 is a right elevational view thereof;

1.9 is a left elevational view thereof;

1.10 is a top plan view thereof; and

1.11 is a bottom plan view thereof.

The broken lines in the reproductions depict portions of the game board having a set of game pieces that form no part of the claim.
